TEXTILE APPARATUS

Basil Gilfrid Barnett Slocombe and Stephen Miller Fulton, Spondon, near Derby, England, assignors to Celanese Corporation of America, a corporation of Delaware

Application March 22, 1946, Serial No. 656,344
In Great Britain April 12, 1945

10 Claims. (Cl. 242—124)

1

This invention relates to textile apparatus and particularly to warp beams, and is especially concerned with warp beams provided with end flanges which are adjustable along the length of the beam barrel so to vary the length of barrel on which the yarn is wound.

In one form of warp beam with adjustable flanges the barrel is formed with a screw thread extending from the ends of the barrel towards the middle, and the flanges are mounted on bosses which are internally threaded so that they can be screwed along the length of the barrel to adjust the position of the flanges along the barrel. Locking collars are provided on the barrel outside the flanges, which are screwed up tightly against the bosses when the flanges are in the desired position so as to prevent accidental rotation of the flanges. This form of beam is very satisfactory in many respects but is open to the disadvantage that the screw threads on the barrel of the beam are liable to be damaged, particularly in the transport, handling and storage of the empty beams, when the flange of one beam is apt to strike against the barrel of another and to damage the unprotected screw threads thereof. It is an object of the present invention to provide a warp beam with adjustable flanges in which this disadvantage is overcome or very substantially reduced.

According to the present invention the flange of a warp beam is carried on the inner end of a long collar that fits over the end of the beam barrel, the beam barrel and part of the bore of the collar being screw-threaded for the attachment and adjustment of the collar and flange, while a part (generally less than one-half) of the length of the bore adjacent to the inner end of the collar is left plain. The plain part of the bore of the collar then covers, in the outermost position of the flange, the screw threads of the barrel that are engaged by the threads of the collar in the innermost position of the flange, and the threads on the barrel are thereby protected against damage. It is desirable to provide locking means for preventing accidental rotation of the flange and collar on the barrel, and consequent disturbance of the adjustment of the flange position.

By the arrangement described above, an adjustment of the flange equal in length to the plain part of the bore is available without any exposure of the screw threads. The assembly may, however, be arranged to give a somewhat greater adjustment since it is permissible for a limited length of the threaded part of the barrel

5 to be exposed inside the flange. Threads exposed immediately inside the flange are not likely to be damaged by the flanges of other beams, since the parts of the flange assembly lying outside the inner face of the flange, e. g. supporting buttresses on the outside of the flange and the collar itself which carries the flange, prevent the edges of the flange from coming into contact with the barrel of another beam close to the flange thereof. 10 While the range of adjustment afforded by the invention is limited this is not a serious disadvantage since it is easy by providing a small number of barrels of different lengths to allow for a wide range of distances between flanges. 15 Moreover it would in any case be highly inconvenient either to have a long overhang of idle barrel with no yarn thereon extending beyond the side frames of the loom, or for the sake of accommodating a long barrel, to use a wide loom 20 for weaving a relatively narrow fabric. The complete beam in accordance with the present invention, with its flange assembly at each end, is light in structure and is, moreover, particularly well adapted to be constructed wholly or to a 25 large extent of light alloy. The adjustment of distances between flanges is quick and easy to make and the flanges of different diameters may be readily exchanged for one another.

While the collar and the flange may be made 30 in one piece, it is more convenient in manufacture to make them as two pieces, a collar that is internally screw-threaded over the whole or the greater part of its length, and a bossed flange having a bore which is partly plain and adapted 35 to fit closely round the barrel of the beam and partly enlarged and screw-threaded in order to be screwed tightly over one end of the collar, the latter being provided with external threads for this purpose. The plain part of the bore of 40 the flange and collar assembly as a whole is thus provided, wholly or in part, by the bore of the flange boss.

The outer surface of the collar may conveniently be formed as a chaingrace or ruffle adapted 45 to be engaged by chains or ropes for controlling the beam let-off in the usual way. The end of the collar may be closed (since the end of the barrel does not extend through it) and arranged to receive a screwed pike or trunnion for convenience in the transport and handling of the beam. For the purpose of mounting the beam in the loom a suitable bearing surface may be provided on the collar outside the chaingrace or ruffle.

A convenient form of locking means to pre-

vent accidental rotation of the flange assembly after it has been adjusted comprises two or more screws extending radially through the thickness of the collar and engaging with flats on the threaded part of the beam barrel. In order to relieve the stress on the locking means it is preferred that the screw threads on the two ends of the barrel should be of appropriate hand and that the beam should be used in such a way that the driving torque during beaming and the braking torque during weaving should tend to drive the flanges inwards along the length of the beam, against the pressure of the yarn wound on the beam. In this way the strain on the locking means is partly balanced and, moreover, there is little tendency for the warp threads to be trapped against the flanges.

The barrel of the beam preferably consists of a tube of light metal of, say, quarter-inch gauge, provided at intervals with slots to receive the tying-on knots of the warp. The barrel may, however, be made of wood with a screw-threaded metal sleeve fitted over each end to receive the flange assembly. The flange and collar may likewise be made of light alloy. Where, however, chains or metal brake-shoes are to be used for controlling the beam let-off, it is preferable to make the collar either of cast malleable iron or of a light alloy on which a surface skin of hard metal, such as chromium, is deposited by spraying or by electro-chemical methods.

By way of example two forms of warp beam according to the invention will now be described in greater detail with reference to the accompanying drawings in which—

Figure 1 is an elevation of one form of beam in which the right-hand end is shown in external view and the left-hand end in section, with its parts separated.

Figure 2 is an outside face view of the beam flange of a second form of beam, and

Figure 3 is a section through a flange assembly incorporating the flange shown in Figure 2.

Referring to Figure 1, the beam comprises a barrel 1 in the form of a light metal tube 6" in diameter and $\frac{1}{4}$ " in thickness slotted every 6" as at 2 to receive the tying-on knots of the warp. The barrel 1 is screw-threaded at both ends 3, 4 for a distance of $5\frac{3}{4}$ ", the threads at 3 being right-hand threads while the threads at 4 are left-hand threads. Into the screw threads at the ends 3, 4 are milled four flats 5 $\frac{3}{8}$ " wide and $3\frac{1}{2}$ " long, parallel to the axis of the barrel 1 and extending to within $2\frac{1}{4}$ " of the ends thereof.

On each end of the barrel 1 is screwed a flange assembly consisting principally of a collar portion 6 and a flange portion 7. The collar 6 is 6" in overall length and its outer surface is formed so as to constitute a bearing surface 8 1" wide for the mounting of the beam in a loom, a chain-grace or brake surface 9 $2\frac{1}{2}$ " wide and a threaded part 10 $1\frac{1}{2}$ " wide. Four holes 12 are bored radially through the threaded part 10 at a distance of $\frac{1}{4}$ " from the inner edge thereof. The bore of the collar 6 is screw threaded over the whole of its length to match the screw thread on the corresponding end of the beam barrel 1 and is closed at the outer end of the collar by means of a disc 13 welded or otherwise secured to the collar. The disc 13 is centrally bored and threaded for the reception of a pike or trunnion 14, which is secured by means of a lock nut 15 disposed on the inner face of the disc 13, and facilitates the handling of the beam and its location during beaming.

The flange member 7 comprises a boss 16, the bore of which (including the flange thickness) is about $3\frac{1}{2}$ " long and fits closely over the barrel 1 for 2" of its length at 17. The remaining part 18 of the bore, $1\frac{1}{2}$ " in length, is enlarged and screw threaded so as to be screwed tightly over the external threaded part 10 of the collar 6. Four radial holes 19 are bored, threaded and countersunk through the boss 16 to correspond with the four holes 12 of the collar 6. The holes 19, 12 receive four locking screws 20 with countersunk heads, the ends of which are adapted to engage with the flats 5 milled on the surface of the beam barrel 1. The screws 20 thus serve the double function of preventing the flange member 7 from turning on the collar 6, and the collar 6 from turning on the barrel 1. The flange 21 itself is $\frac{1}{2}$ " in thickness and is provided with eight radial buttresses 22 extending from the edge of the flange 21 to the boss 16, the buttresses being 1" in width and $1\frac{1}{2}$ " in depth at the boss and tapering away towards the edge of the flange 21.

The form of flange assembly shown in Figures 2 and 3 is adapted to be fitted to a beam barrel of the kind described with reference to Figure 1 and is somewhat lighter in construction than the assembly shown in Figure 1. It comprises, like that of Figure 1, a flange member 25 and a collar member 26. The flange 28 of the flange member is only $\frac{1}{4}$ " in thickness but is reinforced not only by eight buttresses 29 but also by a finger ring 30 1" in depth and 7" in radius and by a further ring 31 about $\frac{3}{8}$ " thick and $\frac{3}{8}$ " deep at the extreme rim of the flange 28. The buttresses 29 are 1" in width and $1\frac{1}{2}$ " in depth where they adjoin the boss 32 of the flange member 25 and taper to $\frac{1}{2}$ " in thickness and $\frac{3}{4}$ " in depth at the edge of the flange 28.

The collar, shown in Figure 3, comprises a 1" bearing surface 33, a chaingrace or ruffle 34 and a threaded portion 35, the three sections being separated by two flanges 36 bevelled to 45° and $\frac{1}{2}$ " in maximum width and thickness. Four holes 37 are bored at equal intervals round the threaded portion 35 to correspond with four holes 38 bored through the thickness of the boss 32 for the reception of locking screws 39. A detachable pike 40, secured by means of a locking nut 41 in the end plate 42 of the collar 26, is also provided.

Each of the beams described above has a flange adjustment of 3" at each end, the adjustment being capable of being made in steps each equal to $\frac{1}{4}$ of the pitch of the screw threads on the barrel 1. The screw threads are completely concealed for the first two inches of the adjustment and only one inch of thread is exposed when the flanges are in their extreme outward position, the threads so exposed being nevertheless protected from damage by the proximity of the flange. By the provision of four interchangeable barrels 1 of 48", 54", 60" and 66" length respectively any width of warp from 36" to 60" can be accommodated.

Having described our invention, what we desire to secure by Letters Patent is:

1. A warp beam flange assembly adapted for attachment to the threaded end of a beam barrel, said assembly comprising a long collar and a flange carried by said collar at the inner end thereof, said collar having part of its bore adjacent to the outer end thereof screw threaded for attachment and adjustment on the beam barrel and having said outer end obstructed to

prevent the emergence therefrom and consequent exposure of the threaded end of said barrel, the part of the bore of said collar adjacent to the inner end thereof being left plain, whereby the plain part of said bore covers, in the outermost position of the flange, screw threads of the barrel that are engaged by the threaded part of said bore in the innermost position of said flange.

2. A warp beam flange assembly adapted for attachment to the threaded end of a beam barrel, said assembly comprising a long collar and a flange carried by said collar at the inner end thereof, said collar having part of its bore adjacent to the outer end thereof screw threaded for attachment and adjustment on the beam barrel and having said outer end obstructed to prevent the emergence therefrom and consequent exposure of the threaded end of said barrel, the part of the bore of said collar adjacent to the inner end thereof being substantially less in length than said screw threaded part and being left plain, whereby the plain part of said bore covers, in the outermost position of the flange, the major part of the screw threads of the barrel that are engaged by the threaded part of said bore in the innermost position of said flange.

3. A warp beam flange assembly adapted for attachment to the threaded end of a beam barrel, said assembly comprising a long collar formed in two parts screwed together end to end and a flange carried by the inner part of said collar at the inner end thereof, the bore of the outer part of said collar being screw threaded for attachment and adjustment on the beam barrel and being obstructed at its outer end to prevent the emergence therefrom and consequent exposure of the threaded end of said barrel, and the bore of the inner part of said collar being left plain whereby the bore of said inner part covers, in the outermost position of the flange, the screw threads of the barrel that are engaged by the threaded bore of the outer part of said collar in the innermost position of said flange.

4. A warp beam flange assembly adapted for attachment to the threaded end of a beam barrel, said assembly comprising a long collar formed in two parts screwed together end to end, locking screws passing radially through both said parts to secure them together and a flange carried by the inner part of said collar at the inner end thereof, the bore of the outer part of said collar being screw threaded for attachment and adjustment on the beam barrel and being obstructed at its outer end to prevent the emergence therefrom and consequent exposure of the threaded end of said barrel, and the bore of the inner part of said collar being left plain whereby the bore of said inner part covers, in the outermost position of the flange, the screw threads of the barrel that are engaged by the threaded bore of the outer part of said collar in the innermost position of said flange, said locking screws being adapted to engage with flats formed on said barrel so as to prevent rotation of the assembly on said barrel after adjustment of the position of the said flange.

5. A warp beam flange assembly adapted for attachment to the threaded end of a beam barrel, said assembly comprising a long collar externally formed near its outer end to constitute a chaingrace, and a flange carried by said collar at the inner end thereof, said collar having part of its bore adjacent to the outer end thereof screw threaded for attachment and adjustment

on the beam barrel and having said outer end obstructed to prevent the emergence therefrom and consequent exposure of the threaded end of said barrel, the part of the bore of said collar adjacent to the inner end thereof being left plain, whereby the plain part of said bore covers, in the outermost position of the flange, screw threads of the barrel that are engaged by the threaded part of said bore in the innermost position of said flange.

10. 6. A warp beam flange assembly adapted for attachment to the threaded end of a beam barrel, said assembly comprising a long collar substantially closed at its outer end, a detachable pike extending from said closed outer end, and a flange carried by said collar at the inner end thereof, said collar having part of its bore adjacent to the outer end thereof screw threaded for attachment and adjustment on the beam barrel, and part of its bore adjacent to the inner end thereof left plain, whereby the plain part of said bore covers, in the outermost position of the flange, screw threads of the barrel that are engaged by the threaded part of said bore in the innermost position of said flange.

15. 7. A warp beam flange assembly adapted for attachment to the threaded end of a beam barrel, said assembly comprising a long collar closed at its outer end and formed in two parts screwed together end to end, a detachable pike extending

30. from said closed outer end, locking screws passing radially through both said parts to lock them together, and a flange carried by said collar at the inner end thereof, the outer part of said collar being externally formed to constitute a chaingrace and having its bore screw threaded for attachment and adjustment on the beam barrel, the inner part of said collar being shorter than the outer part and having its bore left plain whereby said inner part covers, in the outermost

35. 40. position of the flange, the major part of the screw threads of said barrel that are engaged by the threaded outer part of said collar in the innermost position of said flange, said locking screws being adapted to engage with flats formed

45. on the beam barrel so as to prevent rotation of the assembly on the beam barrel after adjustment of the position of the flange.

50. 8. A warp beam comprising a beam barrel screw threaded at each end and carrying at each end a flange assembly comprising a long collar and a flange carried by said collar at the inner end thereof, said collar having a part of its bore adjacent to the outer end thereof and at least as long as the threaded part of said barrel screw

55. threaded for attachment and adjustment on said barrel, and part of its bore adjacent to the inner end thereof left plain whereby the plain part of said bore covers, in the outermost position of the flange, screw threads of the barrel that are engaged by the threaded part of said bore in the innermost position of said flange.

60. 9. A warp beam comprising a beam barrel formed with a right hand screw thread at one end and a left hand screw thread at the other end and carrying at each end a flange assembly

65. comprising a long collar and a flange carried by said collar at the inner end thereof, said collar having a part of its bore adjacent to the outer end thereof and at least as long as the threaded part of said barrel screw threaded for attachment and adjustment on said barrel, and part of its bore adjacent to the inner end thereof left plain whereby the plain part of said bore covers, in the outermost position of the flange, screw

70. 75. threads of the barrel that are engaged by the

7
threaded part of said bore in the innermost position of said flange.

10. A warp beam comprising a beam barrel screw threaded at each end and carrying on each end a flange assembly as claimed in claim 7.
